OTTO C. KADE, DECEASED, ASSIGNOR TO HERSELF INDIVIDUALLY.

REFRESHMENT-TABLE.

1,073,762.

Specification of Letters Patent. Patented Sept. 23, 1913.

Application filed November 8, 1909. Serial No. 526,806.

To all whom it may concern:

Be it known that I, OTTO C. KADE, a citizen of the United States, and a resident of Chicago, Cook county, Illinois, have invented certain new and useful Improvements in Refreshment-Tables, of which the following is a full, true, clear, and exact description, such as will enable others skilled in the art to make and use the same.

10 My invention relates to improvements in furniture for drug stores, ice cream parlors and like places where it is desirable to provide within very limited space, seatings for many people, together with sufficient table surface to accommodate the dishes served to them.

20 The special objects of my invention are to provide a combined table and plurality of seats, which shall be of simple construction, compact and rigid. Second:—to provide a combined table and plurality of seats having a frame in common against which the seats and table are adapted to be folded. Third:—to provide a foldable combined table and 25 plurality of seats which can be easily set up for use and knocked down or folded together, and which shall occupy but a minimum amount of space when in either condition. And fourth:—to provide a foldable 30 combined table and plurality of seats adapted to be folded together or knocked down into a compact rigid form, of such shape that it can be conveniently and safely shipped and which can be easily and quickly set up 35 for use by even an inexperienced person.

Further objects of my invention will appear hereinafter.

With these objects in view my invention consists generally in a combined table and 40 plurality of seats having a supporting frame common thereto.

The invention also consists in a combined table and pair of seats having a supporting frame in common, the table being secured to 45 the supporting frame above and between the seats.

50 The invention consists further and particularly in a foldable combined table and plurality of seats having a common supporting frame, the table and seats being hinged to the back frame, the seat supporting members also being hinged thereto, all of which are adapted to fold against the back frame in such a manner as to form a compact device.

55 In addition to the foregoing my invention

consists in various details of construction and in combination of parts; all as herein-after described and particularly set forth in the claims.

The invention will be more readily understood by reference to the accompanying drawings forming a part of this specification, and which illustrate the preferred embodiment of my invention.

Figure 1 is a perspective view of a foldable combined table and pair of seats, embodying my invention, the same being set up in condition for use; Fig. 2 illustrates the device knocked down or folded together; Fig. 3 is a bottom plan view of the device illustrating it when set up for use; and Fig. 4 is a vertical section substantially on the line X—X of Fig. 1.

In the drawings, 1, designates the back frame of the device. Members, 2, 2', are secured to its ends and extend below the frame, 1, forming the rear legs of the device. Swinging members, 3, 3', are secured respectively to the legs, 2, 2', by suitable hinges, 12, 12'. Members, 4, 4', are secured to the outer ends of the swinging members, 3, 3', at right angles thereto and parallel to the back frame. These extend below the members, 3, 3', thus forming the front legs of the device.

55 5, 5', designate the seats. These are arranged near the outer ends of the back frame and are secured to blocks, 5'', 5''', on the frame, 1, by suitable hinges, 7, 7'. The seats, 5, 5', are further supported by the swinging members, 3, 3', and the legs, 4, 4', take the strain off the hinges, 7, 7'. This is well shown in Figs. 1 and 2. As best shown in Fig. 3 the members, 3, 3', project forward convergingly at an angle to the rear frame, 1; and under the central part of the seats. This is done to form a better bearing for the seat, 5, or in other words to bring the supporting member, 3, 3', nearer under the center of gravity of the weight to be supported.

It is essential that the device when set up for use should be very rigid and substantial, as it must withstand the weight of two people. For this reason the legs, 4, 4', supporting the members, 3, 3', are rigidly secured to the bottom of the seats, 5, 5'. As here shown angle irons, 10, 10', are used for that purpose. There are of course, many other ways of rigidly securing the legs and members, 3,

3', to the seats. For instance, when it is desired to have a device which can be folded up very quickly, the legs, 4, 4', may be secured to the seats, 5, 5', by an automatic catch of a suitable nature.

6 designates the table board which is secured to a block, 1', on the back frame, 1, by suitable hinges, 6'. The table board, 6, is supported in position for use by a suitable bracket, 7², which is hinged to the back frame, so that it may be swung backward against the same.

When the table, 6, is in position for use, the bracket, 7², is centrally secured under it by suitable means such as a screw, 17, passing through a block, 6'', secured to the underside of the table. Other suitable means such as a spring bolt may be used instead of the screw, 17, in case an automatic lock is desired. To prepare the device for use when the same is folded, as shown in Fig. 2, the seats, 5, 5', are raised to a position at right angles to the back frame, 1, and the legs, 4, 4', which swung outward to the position shown in Fig. 3 and there suitably secured to the bottom of the seats, 5, 5'. The table, 6, is prepared for use by raising it to a position at right angles thereto to the back frame, 1, and swinging the bracket, 7², to a central position under the same, where it is suitably secured as before described. To knock down or fold the device, the legs, 4, 4', with the members, 3, 3', after having been detached from the seats, 5, 5', are swung inward parallel to the back frame, 1. The seats, 5, 5', and the table, 6, may be then let down respectively over the members, 3, 3', and the bracket, 7². The purpose of the blocks, 5'', 5''', and the block, 1', is to bring the seats and table, 6, a sufficient distance away from the back frame, 1, so that when folded down they will clear the members, 3, 3', and the bracket, 7².

There are obvious modifications of this invention and one that readily suggests itself is the placing of another set of seats, legs and table on the opposite side of the frame, 1, in which case, four seats and two tables possess a supporting back in common.

As various modifications will readily suggest themselves to one skilled in the art to which this appertains, I do not limit it to

the specific structure herein shown and described.

Having thus described my invention, I claim as new and desire to secure by Letters Patent:

1. In a refreshment table, the combination of a portable back frame, two seats horizontally hinged to said back-frame and spaced apart thereon, a table member horizontally hinged to the back-frame centrally between and above said seats, a vertically hinged bracket secured to the back-frame adjacent each seat, each said bracket having a depending leg at its free end, said brackets being movable to a position beneath the seats further to support them when in use, a vertically hinged bracket secured to the back-frame beneath the table member in position to provide additional support therefor, said seats, table, and brackets all being foldable into intimate parallel relation with the back-frame, as and for the purpose specified.

2. In a refreshment table the combination of a portable back-frame, two seats horizontally hinged thereto and spaced apart thereon, a table member horizontally hinged to the back-frame centrally between and above said seats, a vertically hinged bracket carrying a leg at its free end secured to said back-frame at each side thereof, said brackets extending outwardly and inwardly from the back-frame beneath the seats, means securing the brackets thereto, a horizontally hinged table member secured to the back-frame above and centrally between said seats, a vertically hinged bracket secured to the back-frame beneath the table member, said leg-carrying brackets and table-bracket being foldable into intimate parallel relation with the back frame and said seats and table being foldable over said brackets into parallel relation with the same and with the back-frame and serving to lock the brackets against the back-frame, as and for the purpose specified.

In testimony whereof, I have hereunto set my hand this 5th day of November, 1909, in the presence of two subscribing witnesses

OTTO C. KADE.
